UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

SHOE-SEWING MACHINE.

Original application filed April 7, 1916, Serial No. 89,560. Divided and this application filed November 21, 1919. Serial No. 839,649.

To all whom it may concern:

Be it known that I, FREDERIC E. BERTRAND, a citizen of the United States, residing at Lynn, in the county of Essex and 5 State of Massachusetts, have invented certain new and useful Improvements in Shoe-Sewing Machines; and I do hereby declare the following to be a full, clear, and exact 10 description of the invention, such as will enable others skilled in the art to which it appertains to make and use the same.

The present invention relates to sewing machines and more particularly to thread tensioning devices for shoe sewing machines 15 of the type employing a curved hook needle adapted for fair stitching mock welts and stitched down shoes.

The object of the present invention is to provide a novel and improved thread tensioning device for sewing machines which is simple in construction and efficient in operation.

The features of the present invention comprise certain constructions, arrangements 25 and combinations of parts hereinafter described and claimed, the advantages of which will be obvious to those skilled in the art.

The several features of the present invention will be clearly understood from the following description and accompanying drawings in which:

Figure 1 is a side elevation looking from the right of a shoe sewing machine embodying the features of the invention in their preferred form; Fig. 2 is a front elevation of a portion of the machine illustrated in Fig. 1; and Fig. 3 is a detail side elevation partly in section of portions of the thread 40 tensioning devices.

The machine illustrated in the drawings is a chain stitch shoe sewing machine particularly designed for sewing the out-turned upper to the sole of a stitched down shoe. 45 The machine is provided with a curved hook needle 2, a looper 4, a heating chamber or web 6, a work support 8, a presser foot 10 and a presser foot actuating rod 12 connected to a treadle so that the depression of 50 the treadle depresses the rod which through connecting mechanism raises the presser

foot, and when the treadle is released the rod is moved upwardly and the presser foot is caused to engage the work. The parts above described may be and preferably are the same as the corresponding parts of the machine illustrated and described in applicant's co-pending application Serial No. 89,560, filed April 7, 1916, of which the present application constitutes a division 60 and to which reference may be had for a full and complete description of these parts of the machine.

The illustrated machine is provided with a take-up comprising a take-up thread 65 truck 14 carried on the outer end of a take-up arm 16 of a bellcrank lever, the hub 18 of which is fulcrumed on a hollow stud 20 journaled in bearings formed in arms projecting forwardly from a bracket 70 secured to the machine frame. The other arm 22 of the bellcrank lever is connected by a link 24 to the slotted lower end of an arm 26 of a take-up lever of bellcrank form pivoted at 28 on an upright rising 75 from the base of the machine. The other arm of the take-up lever extends rearwardly and carries a cam roll which engages a cam path formed in the outer side of a cam 30 carried by the main shaft 32 of the machine. 80 After the thread is drawn from the wax pot of the machine, it passes around a large thread truck or tension wheel 34 mounted on a shaft 36 supported in the hollow stud 20, and thence over two small pulleys or thread 85 trucks 40 and 42 which form part of the auxiliary take-up, to the truck 14, from whence it passes under a truck 44 to the looper. The auxiliary take-up comprises a lever 46 pivoted at 48 on the machine frame, 90 and on one end supports a pin on which the thread truck 42 is pivoted. The other end of the auxiliary take-up lever receives one end of a lightly tensioned spring 50, the other end of which is secured to the machine 95 frame. A secondary compression spring 52, more heavily tensioned than the spring 50, is received in a chamber 54 formed on the machine frame, one end of the spring 52 pressing against a shoulder of a plunger 56 100 adapted to reciprocate in the chamber 54 and the other end of the spring taking

against a nut 58 threaded in the open end of the chamber. The nut 58 affords means by which the tension of the spring 52 may be regulated. The movement of the auxiliary take-up lever 46 under the force of the spring 50 is limited by a stop pin 60.

It will be observed from an inspection of the drawings that the tension wheel 34 and the thread trucks of the take-up and auxiliary take-up as well as the truck 44 are located and operate in close proximity to the heating plate forming the right hand wall or surface of the heated chamber or web 6. By means of this construction the 10 radiation from the heating plate keeps the waxed thread as it passes over the trucks on its way to the needle in a pliable and easily workable condition.

In addition to the tension wheel 34, the 20 tension mechanism comprises a brake strap 62 which makes one complete turn around a drum 64 fast on the outer end of the shaft 36, on the other end of which the tension wheel 34 is fixed. One end of the brake 25 strap is secured to the frame of the machine, and the other end is secured to an eye of a bolt 66 loosely received in a hole in a tension lever 68 pivoted on the machine frame. By arranging the brake strap so that it makes 30 one complete turn around the drum 64, the lines of stress upon its ends act in opposite directions. The free end of the tension lever 68 is bifurcated and loosely embraces the 35 presser foot rod 12. A heavy compression spring 70 interposed between the under side of the lever 68 and a projection upon the base of the machine, holds the free end of the lever 68, during the stitch forming operation, against a stop bolt 72 passed through a 40 threaded hole in a lug extending laterally from the machine frame. The operative position of the free end of the lever 68 may be adjusted vertically by means of the bolt 72. A compression spring 74 encircling the 45 upper end of the bolt 66 and secured in position thereon by a nut, by which the tension of the spring may be regulated, tends to maintain the bolt 66 in raised position and imposes on the brake strap the strain 50 requisite to maintain the required amount of tension on the thread. It will be observed by the construction and arrangement of the parts of the tension device that the pull exerted upon the brake strap is such that no 55 cramping strain is imposed upon the shaft 36 because the strain is evenly distributed over the periphery of the pulley 64, and yet an effective clamping strain or gripping action is imposed upon the shaft 36 and the 60 tension wheel 34. The relative arrangement of the tension lever 68 and the presser foot rod is such that, when the operator presses the treadle connected with the presser foot rod, upon the completion of the sewing operation, the downward movement of the 65

presser foot rod brings nuts 76 threaded on the rod into engagement with the upper surface of the free end of the tension lever, thereby depressing it against the upward action of the spring 70 and relieving the tension strap of the strain of the spring 74 to permit the operator to remove the shoe with the thread attached to it from the machine. The space between the nuts 76 and the upper side of the free end of the tension lever is such that, when at the completion of each feeding movement the presser foot rod descends and the presser foot is raised to permit the return of the feed carriage, the nuts do not come into contact with the tension lever and, consequently, the uniform tension exerted by the tension device is not disturbed.

The nature and scope of the present invention having been indicated and a machine embodying the several features of the present invention in their preferred form having been specifically described, what is claimed is:

1. A sewing machine having, in combination, stitch forming devices, a tension wheel, a drum connected therewith, a brake strap embracing the drum connected at one end to a stationary part of the machine, and yielding means connected with the other end of the strap for exerting a strain upon it, the ends of the strap being disposed in opposite directions.

2. A sewing machine having, in combination, stitch forming devices, a shaft, a tension wheel mounted on the shaft, an oscillatory take-up arm pivoted on the shaft, a friction drum secured to the shaft, a brake mechanism acting upon the drum and means for supplying heat to the tension wheel and take-up arm.

3. A sewing machine having, in combination, stitch forming devices, a heating plate, a tension wheel, a take-up arm mounted concentric with the axis of the tension wheel, and a take-up truck mounted on the take-up arm, the tension wheel and take-up truck operating in close proximity to the plate.

4. A sewing machine having, in combination, stitch forming devices, a heating plate, a tension wheel and a take-up truck operating in close proximity to the plate, a drum, a shaft supporting on one end the drum and on the other end the tension wheel, a brake mechanism for the drum, and a take-up arm for supporting the take-up truck pivotally mounted on the shaft between the tension wheel and the drum.

5. A shoe sewing machine having, in combination, stitch forming devices, a work support, a presser foot, a presser foot actuating rod, a tension wheel, and a brake mechanism therefor including a tension lever arranged to be moved by the presser foot actuating rod to release the brake mechanism

when the rod is actuated to raise the presser foot from the work support for the insertion or removal of work.

6. A shoe sewing machine having, in combination, stitch forming devices, a work support, a presser foot, presser foot actuating mechanism, a thread tension wheel, a brake for restraining the rotation of the tension

wheel, a treadle controllable rod, and connections between the rod and the presser foot actuating mechanism and the brake actuated by the rod to raise the presser foot and release the brake upon a movement of the rod. 10

FREDERIC E. BERTRAND
